GERMICIDAL DETERGENT COMPOSITIONS
Kenneth S. Karsten, Westport, and Wilbur S. Taylor, Norwalk, Conn., assignors to R. T. Vanderbilt Company, Inc., New York, N.Y., a corporation of New York
No Drawing. Continuation-in-part of application Ser. No. 85,005, Jan. 26, 1961. This application Oct. 21, 1965, Ser. No. 500,173

7 Claims. (Cl. 252—107)

This application is a continuation-in-part of copending application Ser. No. 306,684, filed Sept. 5, 1963, and now abandoned; application Ser. No. 306,684 is a continuation-in-part of copending application Ser. No. 85,005, filed Jan. 26, 1961, and now abandoned; and application Ser. No. 85,005 is a continuation-in-part of copending application Ser. No. 741,994, filed June 16, 1958, and now abandoned.

The present invention relates to germicidal detergent compositions, and more particularly to hydrophilic skin cleansing compositions comprising a skin substantive germicide. The compositions contemplated by this invention depend upon the presence of 1-hydroxy-2-pyridinethione, salts and esters thereof, and related compounds such as 2,2'-dithio-pyridine-1, 1-dioxide as the substantive germicide.

It has become increasingly desirable to improve the bacteriostatic effect of detergent compositions. The term "detergent" is intended to denote soap and nonsoap surface active agents. Many compounds are known that have germicidal or bacteriostatic properties against specific microorganisms or groups thereof, but such property is generally destroyed or seriously impaired when the compound is incorporated into detergent compositions.

The retention of germicidal properties by a compound after inclusion in a detergent composition is only one of

2

and retaining germicidal activity over a period of time after washing and rinsing of the skin.

Other properties that are not concerned with the germicidal properties directly are, however, important as far as commercial use of the detergent composition by the general public is concerned. These include the following properties of a detergent bar, powder, liquid, etc., after inclusion of the specific compound:

- (1) Initial whiteness.
- (2) Color stability under sunlight exposure.
- (3) Color stability under aging.
- (4) Absence of discoloration by copper in stamping dies.
- (5) Nonirritating to skin.
- (6) No unpleasant odor.

It is an object of this invention to provide a detergent composition which exhibits substantive germicidal properties and has a prolonged effect in maintaining skin germs and bacteria at a reduced level.

It is another object of the present invention to provide a hydrophilic skin cleansing composition comprising a skin-substantive germicide.

It has been discovered that 1-hydroxy-2-pyridinethione compounds when incorporated in detergent compositions retain their bacteriostatic properties and are skin substantive. The use of detergent compositions embodying 1-hydroxy-2-pyridinethione compounds retards the growth of body germs and bacteria for much longer periods than the use of detergent bases.

The specific procedures used to test the properties hereinbefore enumerated are described here in some detail, as there are no established procedures yet widely adopted in the art. The particular pyridinethione compound was blended at various concentrations with detergents which are anionic, cationic, nonionic, amphoteric and mixtures thereof, specific compositions thereof being set forth in Table I.

TABLE I

Code Letter	Percent Detergent Compositions														
	B	C	D	E	F	G	H	I	J	K	L	M	N	O	P
Lux	100														
Ivory		100					50	20		50	20				
Dial			100												
Camay				100											
Cashmere Bouquet					100										
Potassium Oleate						100									
"Ultrawet K" (Anionic)							20	50	70						40
"Aerosol OS" (Anionic)							10	10	10						
"Aerosol A.Y" (Anionic)							18	18	18						
Carboxymethyl Cellulose							2	2	2	2	2	2

Paraffin										30	50		40		
"Intracol OA" (Cationic)													40		
"Antaron FC-34" (Amphoteric)												60	60	60	60
Mixed Phosphates															

Key to Table I

The first five soaps listed are well known proprietary soaps without germicidal agents, composed of a mixture of alkali metal salts of fatty acids, the general composition of "Lux" and "Ivory" being as follows:

Acids	Lux (percent)	Ivory (percent)
Oleic and linoleic	45	46
Stearic	10	14
Palmitic	30	30
Lower Fatty (myristic, lauric, etc.)	15	10

Potassium oleate is a liquid soap formed from 11 parts H₂O, 1 part KOH, 4 parts glycerin and 4 parts red oil (oleic acid).

the necessary or desirable properties the compound must have to be considered as a desirable additive to the detergent composition designed for application to the human body. It is extremely important that the compound exhibit substantivity, i.e., the property of remaining on the skin

"Ultrawet K" is a sodium salt of sulfonated C₁₈ petroleum hydrocarbons.

"Aerosol OS" is a sodium alkyl sulfonate.

"Aerosol A.Y" is diethyl sodium sulfosuccinate.

"Tween 80" is a polyoxethylene sorbitan monooleate.

"Brij 35" is a polyoxyethylene lauryl ether.

"Pluronic F-68" is a condensate of ethylene oxide with a hydrocarbon base formed by condensing propylene oxide with propylene glycol.

"Sterox AJ" is a polyoxyethylene ether.

"Intracol OA" is a long chain fatty acid amide containing several amine groups.

"Antaron FC-34" is a complex fatty amide compound.

70 Bacteriostatic activity per se was tested by taking plugs of the blended solid compositions (liquid compositions were placed in petri-cups) and placing them on separate nutrient agar plates inoculated with *Bacillus subtilis* (found in soil and decomposing organic material), *Staphylococcus aureus* (found on the human skin) and *Sal-*

monella typhosa (cause of typhoid fever). These three bacteria are conventionally used in *in vitro* testing for activity and substantivity. The plates were incubated for 24 hours at about 37° C. and then the diameter of the zone of no bacterial growth around each plug was measured in millimeters (diameter of plug or peni-cup excluded) and recorded.

Substantivity was measured by soaking untanned calf-skin buttons in an 8% aqueous solution of the test soap, then repeatedly rinsing the buttons in distilled water, and subsequently placing the buttons on nutrient agar plates ⁵ inoculated with the same bacteria as noted above. Thereafter, the procedure is the same as following for bacteriostatic activity *per se*. The results are reported in Table II.

Key to Table II: S—*Bacillus subtilis*; A—*Staphylococcus aureus*; T—*Salmonella typhosa*; 1-H-2-P—1-hydroxy-2-pyridinethione; 1-H-2-P, disulfide—2,2'-dithiopyridine-1,1-dioxide; Ziram—Zinc dimethylthiocarbamate; Thiram—Tetramethylthiuram disulfide.

It is clear from the results reported in Table II that the pyridinethione compounds exhibit both bacteriostatic activity and substantivity. Samples number 33 and 50 were further tested in a modification of the split-use hand washing test described by Quinn et al., *Applied Microbiology* 2, 202-4 (1954). In the modified test, first the right hand was uncovered and the left hand covered with a neoprene glove. Then both hands were soaped for 20 seconds by briskly rubbing the moistened medicated test bar with a small amount of wash water held in the cupped hands, the lather being worked up as far as the wrists for 75 seconds, followed by rinsing the hands for 20 seconds while immersed in the wash water and then draining for 20 seconds. Thereafter, the left hand was uncovered, the right hand was covered with a neoprene glove, and the

actual hand washing technique. Various other desirable properties of the same soap-pyridinethione compound mixtures of Table II are reported in Table IV.

The initial whiteness is reported both after mixing of the pyridinethione compound with the soap and after the soap bar had been formed in the conventional brass die.

The sunlight color stability was tested by breaking a soap bar in two and exposing one portion in an east window for two weeks, rotating it one-quarter turn daily.

The heat aging color stability was tested by placing a sample bar in a closed glass jar within an oven at 125° F. for two weeks, which is presumed to be approximately equivalent to one year shelf storage.

The tests reported in Table IV are of the same numbered samples of Table II, but all the samples of Table II were not tested here.

TABLE IV.—COLOR CHANGES DUE TO AGING

Number ¹	Initial Blend	Initial Bar	Heat Aged	Sunlight Aged
1.....	White.....	White.....	Slightly off-white.....	Slightly off-white.....
2.....	do.....	do.....	do.....	Do.....
15.....	Off-white.....	Off-white.....	Brown.....	Brown.....
16.....	White.....	White.....	Off-white.....	Cream.....
17.....	Off-white.....	Off-white.....	Light brown.....	Light brown.....
29.....	White.....	White.....	White.....	White.....

² This slight surface sheen, caused evidently by contact with the brass bar-forming die was removed before the oven and sunlight aging tests.

washing procedure repeated using unmedicated soap, i.e., control soap. Thus, the left hand serves as an unmedicated soap-washed control for the test soap-washed right hand.

The hands of each subject were washed three times each day and bacterial counts made on the wash water used in the second washing on the third and fifth days of the test. The control or unmedicated soap is used for the washings at which bacterial counts are made so that none of the test compound is present in the wash water to influence the results. Aliquots of the wash water in which each hand is washed were added to nutrient agar pour plates within one minute after completion of washing. The plates were incubated for 48 hours at 37° C., the bacterial colonies counted and the results calculated for the entire wash water. The results are summarized in Table III:

It will be noted that samples 29 and 33 (zinc salt of 1 - hydroxy - 2 - pyridinethione) gave excellent results in the color tests and, in fact, slightly better than the control bars containing no bacteriostatic agent. Samples 48 and 50 (2,2' - dithiopyridine - 1,1 - dioxide) were also fairly good except for the surface sheen on the initial bar, a feature which might be overcome by changing the bar-forming conditions or dies.

The soaps showing the more desirable results in the color tests were subjected to bacteriostatic and substantivity tests after heat aging in an attempt to determine the extent of loss of bacteriostatic effect, if any, during heat aging. The B ("Lux") soaps were aged for six weeks, a very severe test, while the C ("Ivory") soaps were tested after the normal two weeks aging at 125° F., as described for Table IV. Bacteriostatic activity and

² Tr.—Growth touching button in one place.

After the aging tests, these samples retained their bacteriostatic activity and substantivity.

Detergent compositions N, O, P and Q were dry granular formulations of heavy-duty laundry type to which were added for separate test 1% by weight of zinc, so-

dium, disulfide and cetyl ammonium derivatives of the 1-hydroxy-2-pyridinethione. It was found that fabrics washed with these formulations had drastic reductions in bacteria count relative to fabrics washed in the same formulation without the active agent and further that this reduction was partly maintained after rinsing. Fabrics laundered in this manner would be particularly useful for wear or use that contacts the skin, or where large numbers of bacteria are encountered such as hospital or diaper laundries.

No skin irritation has been noted with any of the pyridinethione compounds tested.

The pyridinethione compounds do not impart odors to a detergent composition. This is a property highly desirable to both the manufacturer and the user of the detergent.

Not only do the pyridinethione compounds have excellent germicidal and substantive properties, which are maintained after prolonged aging, but these compounds also give excellent results in the various color tests which are so important in offering soap to the consumer market. As will be noted, many of the compounds stay white through the heat aging and sunlight aging tests and the others have only slight discoloration.

The specific examples reported in the tables have included 0.07 to 5% by weight of the pyridinethione compounds in the detergent composition (based on solids) in order that specific comparisons could be made with the various compounds and also with various controls and prior art compounds. However, it will be obvious that a wider range of pyridinethione compounds can be used and we have found from 0.01 to 10% to be generally a satisfactory range, although this should not be a limiting feature of our invention.

It is obvious from these results that the 1-hydroxy-2-pyridinethione and its derivatives have properties which indicate their use as an ingredient of a germicidal or medicinal soap or detergent.

This invention is concerned with 1-hydroxy-2-pyridine-thione (and derivatives) which has the following structural formula in tautomeric form, the sulfur being attached to No. 2 position of the pyridine ring:

The salts and esters disclosed herein represent substitution of the corresponding cation for the hydrogen of one of the tautomeric forms. Depending, of course, on the valence of the cation involved, there may be more than one of the 1-hydroxy-2-pyridinethione rings in the compound. Although a number of compounds have been

specifically disclosed, it will be apparent to one skilled in the art that inorganic salts other than those tested are suitable. Further, other amine salts, quaternary ammonium salts and other esters are also suitable. The disulfide (2,2'-dithiodipyridine 1,1'-dioxide) represents the attachment of two 1-hydroxy-2-pyridinethione rings by the elimination of the two hydrogens from the sulfur atoms to give a sulfur-to-sulfur linkage. Other substituted or derived compounds of 1-hydroxy-2-pyridinethione which retain the bacteriostatic and substantive properties are considered to be within the scope of this invention.

The active pyridineethione compounds may be incorporated into liquid, bar or powder detergent compositions as desired to satisfy the particular product requirement. The detergent compositions herein are hydrophilic, but the composition as a whole may include hydrophobic components, e.g., paraffin. Detergent compositions may, of course, include conventional additives such as perfume, color, emollients, binders, inert fillers, etc.

20 What is claimed is:

20 1. A hydrophilic skin cleansing composition consisting
essentially of at least one synthetic organic detergent
selected from the group consisting of nonsoap anionic,
nonionic, cationic and amphoteric detergents and fatty acid
25 soaps and a germicide selected from the group consisting
of 1-hydroxy-2-pyridinethione, 2,2'-dithiopyridine-1,1-di-
oxide, and inorganic metal salts of 1-hydroxy-2-pyridinethione
30 in which the cation is selected from the group con-
sisting of sodium, zinc, titanium, iron, manganese, zircon-
ium, tin, cadmium, and barium, in an amount of from
about .01% to about 10% by weight, said germicide being
both skin-substantive and germicidally active in said com-
position.

2. A hydrophilic skin cleansing composition consisting essentially of at least one synthetic organic detergent selected from the group consisting of nonsoap anionic, nonionic, cationic and amphoteric detergents and fatty acid soaps and nonsoap surface active agents, and a germicide consisting of an inorganic salt of 1-hydroxy-2-pyridinethione in which the cation is selected from the group consisting of sodium, zinc, titanium, iron, manganese, zirconium, tin, cadmium and barium, in an amount of from about .01% to about 10% by weight, said germicide being both skin-substantive and germicidally active in said composition.

43 in said composition.

3. A hydrophilic skin cleansing composition consisting essentially of at least one synthetic organic detergent selected from the group consisting of nonsoap anionic, nonionic, cationic and amphoteric detergents and fatty 50 acid soaps and nonsoap surface active agents, and a germicide consisting of the zinc salt of 1-hydroxy-2-pyridine-thione in an amount of from about .01% to about 10% by weight, said germicide being both skin-substantive and germicidally active in said composition.

55 4. A hydrophilic skin cleansing composition consisting essentially of at least one synthetic organic detergent selected from the group consisting of nonsoap anionic, nonionic, cationic and amphoteric detergents and fatty acid soaps and nonsoap surface active agents, and a germicidal composition consisting of the cadmium salt of 1-hydroxy-2-pyridinethione in an amount of from about .01% to about 10% by weight, said germicide being both skin-substantive and germicidally active in said composition.

60

5. A hydrophilic skin cleansing composition consisting
65 essentially of at least one synthetic organic detergent
selected from the group consisting of nonsoap anionic,
nonionic, cationic and amphoteric detergents and fatty
acid soaps and nonsoap surface active agents, and a germi-
cide consisting of the tin salt of 1-hydroxy-2-pyridine-
70 thione in an amount of from about .01% to about 10%
by weight, said germicide being both skin-substantive and
germically active in said composition.

6. A hydrophilic skin cleansing composition consisting essentially of at least one synthetic organic detergent selected from the group consisting of nonsoap anionic

nonionic, cationic and amphoteric detergents and fatty acid soaps and nonsoap surface active agents, and a germicide consisting of the zirconium salt of 1-hydroxy-2-pyridinethione in an amount of from about .01% to about 10% by weight, said germicide being both skin-substantive and germicidally active in said composition.

7. A hydrophilic skin cleansing composition consisting essentially of at least one synthetic organic detergent selected from the group consisting of nonsoap anionic, nonionic, cationic and amphoteric detergents and fatty acid soaps and nonsoap surface active agents, and a germicide consisting of the titanium salt of 1-hydroxy-2-pyridinethione in an amount of from about .01% to about 10% by weight, said germicide being both skin-substantive and germicidally active in said composition.

10% by weight, said germicide being both skin-substantive and germicidally active in said composition.
